TRAFFIC SIGNALING SYSTEM

Ronald A. McCann, Swissvale, Pa., assignor to
The Union Switch & Signal Company, Swiss-
vale, Pa., a corporation of Pennsylvania

Application March 1, 1939, Serial No. 259,203

6 Claims. (Cl. 246—130)

My invention relates to traffic signaling systems, and particularly to traffic signaling systems for controlling the movements of two or more classes of traffic, the movement of one class of which is given preference at all times.

A feature of my invention is the provision of novel and improved means for controlling two or more classes of traffic which operate over intersecting traffic routes, wherein one class of traffic is given preference over other classes, and wherein when the preferred class is given the right-of-way to proceed, the other classes are controlled to prevent all traffic movements interfering with the movement of such preferred class.

Apparatus embodying my invention is particularly well adapted for controlling highway traffic on one traffic route turning onto another traffic route and crossing a railway track intersecting the other traffic route.

Other features and advantages of my invention will appear as the specification progresses.

I shall describe one form of apparatus embodying my invention, and shall then point out the novel features thereof in claims.

The accompanying drawing is a diagrammatic view of a preferred form of apparatus embodying my invention when applied to a traffic signaling system controlling the intersection of two highway traffic routes, one route of which is paralleled by a stretch of railway track which intersects the other traffic route at grade at the intersection of the traffic routes.

Referring to the drawing, the reference character A designates one traffic route, and the reference character B designates another traffic route, which routes intersect each other at grade. A stretch of railway track, designated by the reference character C, as shown parallels route B and intersects route A at grade. Although track C is shown contained within route B, it is to be understood that I do not confine myself to an intersection as shown, but that the scope of my invention embraces any signaling system for an intersection of two interfering traffic routes wherein traffic on one route is permitted to cross an intersecting route but is prevented at times from turning onto such intersecting route and across another traffic route intersecting such intersecting traffic route.

To aid in the understanding of my invention, I shall consider route A as being a north and south road with northbound traffic moving from the bottom to the top of the drawing and southbound traffic moving from the top to the bottom. Route B I shall speak of as an east and west

road with eastbound traffic moving from the left to the right of the drawing and westbound traffic moving from the right to the left. The railway C I shall consider as a single track railway over which trains move in both eastbound and westbound directions.

Traffic at the intersection of routes A, B and C is governed by four right-of-way signals, one located at each corner and designated by the reference characters D, E, F and H, and by two turnout signals LT¹ and LT². Signal D governs southbound traffic moving on route A, signal E governs northbound traffic moving on route A, signal F governs westbound traffic moving on route B, while signal H governs eastbound traffic moving on route B. Signals F and H, as will appear more clearly hereinafter, are at times controlled by the operation of trains operating on track C, and in turn may serve to control the operation of such trains by indicating that the signaling apparatus is properly conditioned for a train movement across the highway intersection. To more readily distinguish signals F and H from signals D and E, I shall refer to the first pair of signals as being railway-highway right-of-way signals since they may control either or both railway and highway traffic, and the latter pair of signals I shall refer to as being highway right-of-way signals since they control only highway traffic. While signals D, E, F and H may take different forms, a preferred form is that wherein each signal comprises three distinctively colored lights, preferably a green, a yellow and a red light, designated respectively by the reference characters G, Y and R. In accordance with the usual practice, the lamps for each pair of signals D, E and F, H are adapted to be lighted so that the signals alternately indicate proceed to one traffic route while indicating stop to the other intersecting route, and then indicate proceed to the other traffic route while indicating stop to the one traffic route. The signals are usually further controlled to display each a yellow or caution signal intermediate each display of the proceed and stop indications for indicating that a change is being effected in the right-of-way indication for each traffic route. As will be presently explained, the display of the proceed and caution and stop indications for each right-of-way signal is controlled by a signal timer ST.

The two turnout signals LT¹ and LT² are located one adjacent each railway-highway signal F and H, respectively, for controlling traffic operating over route B turning onto route A across

track C. Signals LT¹ and LT² may take different forms and as here shown each comprises two differently colored directional signals each in the form of an arrow with the head pointed 5 in the direction of the traffic moves which the signal is adapted to control. Preferably, the turnout signals are located on the signal mast of the associated railway-highway signals below the latter signals, and are provided each 10 with a green directional arrow LP and a red directional arrow LS. As will be explained presently, the turnout signals are normally controlled by the signal timer ST in step or register with their associated railway-highway signals, 15 that is to say, the green directional arrow LP is illuminated when the green proceed indication G is displayed by its associated railway-highway signal, and the red directional arrow LS is displayed when its associated railway-highway 20 signal displays its red or stop indication R, but at times the turnout signals are controlled out of register with the associated railway-highway signals so that the turnout signals display the red directional arrows LS when the associated 25 railway-highway signals display the green or proceed indications G.

The signal timer means ST, previously referred to, may take any one of many suitable forms, and as here shown comprises three drums 30 or cams 5, 6 and 7 which are secured to a shaft 8 and which rotate in response to the actuation of a motor M connected with the shaft 8 by a suitable train of gears indicated on the drawing by a dash line. Each of the cams 5, 6 and 7 35 is provided with a high or contact making surface and with a low or contact breaking surface. Cam 5 is adapted to engage with its contact making surface a contact member 9 to close a circuit controlling contact 9-10 once for each 40 complete rotation of the shaft 8, cam 6 is adapted to engage with its contact making surface a contact member 11 to close a circuit controlling contact 11-12, the contact 11-12 being closed two times in each complete revolution of 45 the shaft 8, and cam 7 is adapted to engage with its contact making surface a contact member 13 to close a circuit controlling contact 13-14 once for each complete revolution of the shaft 8. The 50 contact members 9, 11 and 13 are each biased by suitable means, not shown, so as to ride on the low portion of their associated cams to open the respective contacts 9-10, 11-12 and 13-14 when the shaft 8 is rotated to bring the lowered portion of the cams into engagement with the 55 respective contact members. The high or contact making portions of the cams 5, 6 and 7 are so proportioned that starting from the position shown, cam 5 closes contact 9-10 for 120° 60 rotation of the shaft 8 in a counterclockwise direction, cam 6 closes contact 11-12 for the next 60° rotation of the shaft, cam 7 closes contact 13-14 for the next 120° rotation of the shaft, and cam 6 again closes contact 11-12 for the last 60° rotation of the shaft 8 in the counterclockwise direction. It follows that with motor 65 M rotating shaft 8 at a uniform speed, the above cycle of operation for the contacts 9-10, 11-12 and 13-14 will be periodically repeated to provide a definite period of time during which each 70 contact is closed. Contact 9-10 of signal timer ST is included in an operating circuit extending from the BX terminal of a suitable source of current, such as the secondary winding 15 of a transformer, the primary winding 16 of which 75 is connected with a generator not shown, through

contact 9-10, then through the lamps G of signals F and H and the lamps R of signals D and E in parallel, and thence to the other terminal CX of winding 15 of the transformer. In order to simplify the drawing, the lamps G, Y and R 5 for the signals D, E, F and H, when shown in circuit with the control contacts, are shown for convenience grouped together and not at their actual location on the respective corners of the intersection of routes A, B and C, it being understood 10 that actually each lamp for the right-of-way signals is located at the intersection as indicated in the drawing by the signals D, E, F and H there positioned.

The directional arrows LP for turnout signals 15 LT¹ and LT² are normally operated in parallel with the lamps G of signals F and H and lamps R of signals D and E, the circuit for the arrows LP being the same as the above traced circuit 20 through contact 9-10 of signal timer ST, and then passing through front contact 17 of a relay LTR to be referred to later, and the lamps of arrows LP of signals LT¹ and LT², in parallel, to terminal CX. The lamps of the directional arrows LP and LS are shown for convenience 25 grouped near the lamps of signals D, E, F and H, it being understood that in actual practice such lamps will be located at the intersection of routes A, B and C as indicated in the drawing.

Contact 11-12 of signal timer ST is interposed 30 in an operating circuit for lamps Y of signals D, E, F and H, the circuit passing from the BX terminal through contact 11-12 of signal timer ST, and the lamps Y of signals D, E, F and H 35 in parallel, to terminal CX.

Contact 13-14 of signal timer ST is interposed 40 in an operating circuit extending from terminal BX through contact 13-14, the lamps R of signals F and H and the lamps G of signals D and E in multiple, and then to terminal CX. The directional arrows LS of signals LT¹ and LT² are normally operated in parallel with the lamps R of signals F and H and the lamps G of signals D and E, the circuit for the arrows LS being the same as the just traced circuit 45 for lamps R of signals F and H and lamps G of signals D and E, through contact 13-14, and then passing through front contact 18 of relay LTR and the lamps of arrows LS of signals LT¹ and LT² in parallel, to terminal CX.

From the foregoing, it is apparent that when motor M of signal timer ST is energized in a manner to be described presently, during the first 120° operation of the signal timer the lamps R of signals D and E are illuminated to indicate 55 stop to traffic on street A, the lamps G of signals F and H are illuminated to indicate proceed to traffic on street B and track C, and the directional arrows LP of signals LT¹ and LT² are 60 illuminated to indicate that traffic on street B is permitted to turn left from street B onto street A and across track C. During the next 60° operation of the signal timer, the yellow lamps Y of signals D, E, F and H are illuminated to indicate 65 to all traffic that the right-of-way indication is about to be changed, and the directional arrows LP and LS of signals LT¹ and LT² are dark. During the next 120° operation of the signal timer, the lamps G of signals D and E are illuminated 70 to display proceed to traffic on street A, the lamps R of signals F and H are illuminated to display stop traffic on street B and track C, and the directional arrows LS are illuminated to indicate that traffic on street B is prevented from 75 turning off street B on to street A and across

tracks C. Then, during the last 60° operation of the signal timer, the yellow lamps Y of signals D, E, F and H are illuminated to indicate that the right-of-way indication is about to be changed, and the directional arrows LS and LP of signals LT¹ and LT² are dark. This operating cycle for the control of the right-of-way signals D, E, F and H, and of the turnout signals LT¹ and LT², will be periodically repeated as long as motor M of the signal timer ST is energized.

In order to establish preference for one class of traffic over the other class of traffic at the intersection of routes A, B and C, the track rails 1 and 1a of track C are divided by means of the usual insulated track joints 2 into track sections M—M and N—O, which extend in opposite directions from the intersecting traffic route A. The track sections M—N and N—O are provided with track circuits here shown comprising in each instance a suitable source of current, such as track battery 3, connected across the track rails at one end of the section, and one winding W¹ or W², respectively, of an interlocking relay XR connected across the track rails at the other end. The winding W¹ and W² of relay XR are responsive each to the presence of trains upon the associated track section, but are arranged so that only the first winding of the two windings to be successively deenergized is permitted to open or close its control contacts, the other winding being held at an interlocked position in which the winding cannot open or close its control contacts, when this other winding is deenergized during the interval that the first winding is still deenergized. The relay XR may take any one of many well-known forms, one type of which is shown and described in United States Letters Patent No. 1,799,629, granted to W. K. Lockhart and T. J. O'Meara on April 7, 1931.

The reference character MR designates a control relay governed jointly by relay XR and by signal timer ST, for controlling signal timer ST to retain the railway-highway signals F and H at a cleared condition when trains approach the intersection of the track C and the street A from either direction. A circuit for relay MR may be traced from terminal BX through contact 9—10 of signal timer ST, back contact 19 or 20 of winding W¹ or W², respectively, and the winding of relay MR to terminal CX. A control circuit for motor M of signal timer ST passes from terminal BX through back contact 21 in multiple with back contact 22 of relay MR, and the motor M to terminal CX. From the foregoing it is apparent that when relay MR is released motor M is energized and operates signal timer ST to thereby effect cyclic operation of signals D, E, F, H, LT¹ and LT², but that relay MR is picked up when contact 9—10 of timer ST is closed and winding W¹ or W² of relay XR is released by a train on track C approaching street A, to terminate the operation of timer ST and to retain contact 9—10 of that timer closed. Contact 9—10 of timer ST closed completes the circuits whereby signals F and H indicate proceed and signals D and E indicate stop.

The reference character LTR designates a control relay governed by winding W¹ or W² of relay XR, for at times conditioning turnout signals LT¹ and LT² for operation by signal timer ST in step or register with the associated railway-highway signals F and H. Relay LTR is normally energized over a circuit passing from terminal BX through front contact 23 and front contact 24 of winding W¹ and W², respectively, of relay XR,

and the winding of relay LTR to terminal CX. The front contacts 23 and 24 of relay XR are characterized, as pointed out hereinbefore, by the fact that each contact is opened only when its associated winding of the interlocking relay is the first winding of the two to be successively deenergized, so that relay LTR will be released only when its circuit is opened by the releasing of winding W¹ or W² according as such winding is the first to be deenergized. When relay LTR is released, the relay completes a simple circuit passing from the BX terminal through its back contact 25, and the lamps of directional arrows LS of signals LT¹ and LT², in multiple, to terminal CX. As was pointed out hereinbefore, relay LTR when picked up completes at front contact 17 or 18, the operating circuits for directional arrows LS and LT, respectively, of signals LT¹ and LT², whereby signals LT¹ and LT² are normally operated in register with the associated railway-highway signals F and H. It is readily apparent from the foregoing that when relay LTR is released, signals LT¹ and LT² are removed from control by the signal timer means ST, and are controlled to their distinctive indications over back contact 25 of control relay LTR.

In describing the operation of the apparatus embodying my invention, I shall first assume that no train on track C is approaching the intersecting street A within the limits of the track sections M—N and N—O. With sections M—N and N—O unoccupied, windings W¹ and W² of relay XR are picked up, holding the circuit for relay MR opened so that relay MR is released, and the circuit for relay LTR closed so that relay LTR is picked up. As was pointed out hereinbefore, with relay MR released the circuit for motor M is completed so that the signal timer ST operates to cyclically control the operation of the right-of-way signals D, E, F and H, at a uniform rate and in a manner such that the signals are alternately cleared for each street. And with relay LTR picked up, signals LT¹ and LT² are conditioned for operation by signal timer ST in register with the operation of the associated signals F and H.

I shall now assume that an eastbound train, operating on track C, enters section M—N on its way toward the intersecting street A. When this happens, winding W¹ is released to open its front contact 23, thereby opening the circuit for relay LTR whereupon that relay releases to remove the signal timer ST from control of the turnout signals LT¹ and LT², and to control directional arrows LS to their illuminated condition. The display of the illuminated red arrows LS of signals LT¹ and LT² now operate to prevent traffic operating on street B from turning onto street A and across track C. Winding W¹ in releasing also closes its back contact 19 so that when signal timer ST is operated to close its contact 9—10, the circuit previously traced for relay MR is completed whereupon that relay picks up to open its back contacts 21 and 22 and thereby deenergize motor M of timer ST. It is readily apparent that with motor M deenergized, contact 9—10 of timer ST is held closed to complete the energizing circuits for lamps G of signals F and H and lamps R of signals D and E. It follows that traffic on track C is granted right-of-way preference when a train approaches the intersecting street A, that highway traffic on street B is signaled to proceed parallel with the track C, but is prevented from turning left from street B across track C and onto street A, and that

traffic on street A is signaled to prevent traffic movements across street B and track C. As pointed out hereinbefore, signals F and H may also be used to control railway traffic, and the display of the green G indication of signal H would indicate a proceed signal to the eastbound train, thereby informing the engineman of that train that the intersection is properly signaled for train movements. It is readily apparent, therefore, that the highway crossing is signaled to permit non-interfering movements when a train approaches the intersection, but all highway traffic movements interfering with the preferred movement of the railway traffic are prevented.

When the train enters section N—O and winding W2 is deenergized, the interlocking feature of the relay XR prevents front contact 24 from opening and back contact 25 from closing, so that when the train vacates section M—N and winding W1 picks up, the circuit for relay LTR is reestablished whereupon that relay picks up to condition signals LT1 and LT2 for operation by signal timer ST, and relay MR is released to reestablish the circuit for motor M to restore the cyclic operation of the signal timer and of the right-of-way and turnout signals. Then, when the train vacates section N—O, winding W2 reenergizes to restore relay XR to its normal condition.

The operation of the apparatus for a westbound train approaching street A is substantially similar to the operation just described for an eastbound train, as can readily be understood from an inspection of the drawing, and further detailed description is deemed unnecessary.

From the foregoing description of the operation of the apparatus embodying my invention, it is readily apparent that I have provided a signaling system for normally cyclically controlling traffic of one class operating over interfering traffic routes, but which at times establishes preference to a superior class of traffic operating over a traffic route interfering with such other traffic routes. Furthermore, it is apparent that when the superior class of traffic is granted preference in movement, all movements of the one class of traffic which might interfere with the movements of the superior class are prevented.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a stretch of railway track intersected by a first traffic route, a second traffic route intersecting said first traffic route, railway-highway signals for governing traffic movements on said second traffic route across said first traffic route, turnout signals for governing traffic movements on said second traffic route turning onto said first traffic route, highway signals for governing traffic movements on said first traffic route across said second traffic route and said railway track, a timing device, means for normally energizing said timing device, means controlled by said timing device when energized for clearing said highway signals alternately with said railway-highway signals, a control relay, means for normally energizing said control relay, means controlled by said control relay when energized for conditioning said turnout signals for cyclic operation by said timing device in register with the

operation of said railway-highway signals, means governed by said control relay when deenergized for controlling said turnout signals to the danger condition, and means governed by a train on said railway track effective when said train is approaching said first traffic route from either direction for deenergizing said control relay and for deenergizing said timing device for retaining said railway-highway signals in the cleared condition and effective when said train is receding from said traffic route for reenergizing said control relay and said timing device.

2. In combination, a stretch of railway track intersected by a first traffic route, a second traffic route intersecting said first traffic route, railway-highway signals for governing traffic movements on said second traffic route across said first traffic route, turnout signals for governing traffic movements on said second traffic route turning onto said first traffic route, highway signals for governing traffic movements on said first traffic route across said second traffic route and said railway track, a timing device, means for normally energizing said timing device, a control relay, means for normally energizing said control relay, means governed by said control relay when energized for normally conditioning said turnout signals for control by said timing device, means governed by said control relay when deenergized for controlling said turnout signals to the danger condition, means governed by said timing device when energized for clearing said highway signals alternately with said railway-highway and turnout signals, means governed by a train on said railway track effective when said train is approaching said first traffic route from either direction for deenergizing said timing device for retaining said railway-highway signals at the cleared condition and for deenergizing said control relay, and directional means governed by said train when receding from said traffic route for causing said timing means to become energized and for causing said control relay to become energized.

3. In combination, a stretch of railway track intersected by a first traffic route, a second traffic route intersecting said first traffic route, railway-highway signals for governing traffic movements on said second traffic route across said first traffic route, turnout signals for governing traffic movements on said second traffic route turning onto said first traffic route, highway signals for governing traffic movements on said first traffic route across said second traffic route and said railway track, a timing device, means for normally energizing said timing device, a control relay, means for normally energizing said control relay, means governed by said control relay when energized for conditioning said turnout signals for control by said timing device, means governed by said timing device when energized for clearing said highway signals alternately with said railway-highway and turnout signals, means governed by a train on said railway track effective when said train is approaching said first traffic route from either direction for deenergizing said timing device for retaining said railway-highway signals at the cleared condition and for deenergizing said control relay, means governed by said control relay when deenergized for controlling said turnout signals to the danger condition, and directional means governed by said train receding from said first traffic route for causing said timing device and said control relay to become reenergized.

4. In combination, two traffic routes intersecting at grade and each having means for displaying right-of-way signal indications, a stretch of railway track adjacent one of said traffic routes and intersecting the other of said traffic routes at grade, turnout signal means for controlling traffic movements on said one route turning onto said other route and across said railway track, signal timer means for normally cyclically displaying 5 said right-of-way indications successively to said two traffic routes, a control relay, means governed by said control relay when energized, for conditioning said turnout signals for operation by said signal timer means in step with the right-of- 10 way indications displayed to said one traffic route, means governed by a train on said railway track effective when said train approaches said other traffic route from either direction for controlling said signal timer means to display right-of-way 15 signal indications to said one traffic route and for deenergizing said signal control relay, and means governed by said control relay when deenergized to control said turnout signals to the danger condition.
5. In combination, two traffic routes intersecting at grade and each having means for displaying right-of-way signal indications, a stretch of railway track adjacent one of said traffic routes and intersecting the other of said traffic routes 20 at grade, turnout signal means for controlling traffic movements on said one traffic route turning onto said other traffic route and across said railway track, signal timer means for normally cyclically displaying said right-of-way indications 25 successively to said two traffic routes, signal control means for normally conditioning said turnout signal means for control by said signal timer 30 means in register with the control of the right-of-way indication for said one traffic route, other means governed by said signal control means for operating said turnout signals to the danger condition, and means governed by a train on said railway track effective when said train is approaching said other traffic route for rendering said signal timer means ineffective to cyclically display said indications and to give the right-of-way indication to said one traffic route and for rendering said signal control means ineffective to condition said turnout signals for control by said signal control means and to control said signal control means to operate said turnout signals to the danger condition. 35
6. The combination in a signaling system having means for cyclically operating right-of-way signals to display right-of-way indications successively to each of two intersecting traffic routes, one route of which contains a stretch of railway track intersected at grade by the other traffic route, of auxiliary signals for controlling traffic in one of said two traffic routes, means normally effective for operating said auxiliary signals in step or register with the right-of-way signals of the associated one of said two traffic routes, means controlled by a train on said stretch approaching the intersecting traffic route for terminating the cyclic operation of said right-of-way signals to cause right-of-way indications to be displayed to the one of said two traffic routes containing the stretch of railway track, and other means controlled by said train approaching the intersecting traffic route for controlling said auxiliary signals to display indications out of register with said associated right-of-way signals. 40

RONALD A. McCANN.
